Primary Examiner — Rosemary K Tarcza*Assistant Examiner* — Christy M Nemeth(74) *Attorney, Agent, or Firm* — Banner & Witcoff, Ltd.**CLAIM**

The ornamental design for an insulating device, as shown and described.

DESCRIPTION

FIG. 1 is a top, front, right perspective view of an insulating device showing our new design;

FIG. 2 is a front view thereof; and,

FIG. 3 is a rear view thereof.

The broken lines in the drawings are for the purpose of illustrating portions of the insulating device that form no part of the claimed design.
